UNITED STATES PATENT OFFICE.

HENRY C. EGERTON, OF RIDGEWOOD, NEW JERSEY.

GRIPPING SHOE-SOLE.

1,352,731.

Specification of Letters Patent. Patented Sept. 14, 1920.

Application filed October 1, 1918. Serial No. 256,369.

To all whom it may concern:

Be it known that I, HENRY C. EGERTON, a citizen of the United States, and resident of Ridgewood, county of Bergen, State of New Jersey, have made a certain new and useful Invention Relating to Gripping Shoe-Soles, of which the following is a specification, taken in connection with the accompanying drawing, which forms part of the same.

This invention relates especially to gripping rubber shoe sole elements, such as separate soles or heels or shoe soles having attached or integral heel portions which are provided with gripping apertures or holes of the golf cup type and in which these gripping apertures are provided with reinforcing members or cups embedded in and united to the sole composition and comprising fibrous material impregnated with and stiffened by cured incorporated phenolic condensation cementing material. Such cups or members which may of course have a round or other suitable outline on the wearing surface of the sole, may be formed of any suitable fibrous material, such as cloth, paper, chopped lengths of more or less wound or shaped cotton or other fiber, paper pulp or the like carrying or more or less impregnated with suitable phenolic condensation cementing material, such, for instance, as bakelite, condensite or redmanol varnish compositions so that when cured the reinforcing members are greatly stiffened and strengthened so as to resist wear or deformation and preserve the shape of these gripping apertures so that the shoe sole element continues to effectively grip the ground. Where, as is sometimes desirable, the shoe sole is provided with an incorporated stiffening element or layer of fabric or fibrous material carrying such cured phenolic condensation cementing material of the type covered by my co-pending application 244,340, filed July 1, 1918, it is in some cases desirable to more strongly secure the aperture reinforcing member in position in the sole element and this can be done by more or less directly cementing it to the main stiffener member or sheet by bringing the two surfaces together so that the incorporated phenolic condensation cementing material may strongly unite them. For some purposes, however, it is preferable to have at least some relative movement between these parts so as to somewhat cushion the impacts to which the reinforcing cup is sub-

jected and this may be secured by interposing a greater or less thickness of the rubber sole composition between these two relatively stiff strong members. It is usually preferable to have the inner surfaces of these reinforcing cups or members of a somewhat flaring or conical shape so as to promote their self-clearing action in facilitating the dropping or discharge of dirt therefrom and this self-clearing action may be promoted by giving the reinforcing cups a smooth inner surface which may be effected by the use of a smooth molding plug or member there-in when the final curing treatment occurs.

In the accompanying drawing showing in a somewhat diagrammatic way various illustrative embodiments of this invention,

Figure 1 is a perspective view of a shoe sole member, parts being shown in section for greater clearness.

Fig. 2 is an enlarged transverse section showing a part of such a sole member and the coöperating mold sections which may be used for forming the same; and

Figs. 3 to 8 show similarly enlarged sections illustrating different forms of such reinforcing cups or members and arrangements thereof within the shoe sole elements.

As indicated in Fig. 1, the shoe sole element 1 may in some cases though not necessarily comprise a sole and integral heel which may have a wearing surface 7 of rubber or other suitable composition, such as a strong rubber sole composition which may for some purposes be of relatively pure strong rubber, such as tire stock, in which more or less short fibrous material may be incorporated, if desired. This rubber sole 7 may, if desired, be stiffened and strengthened by being permanently cemented to a stiffening member adjacent one side of the sole element and which may comprise one or more sheets or layers 2, 3 of canvas or other suitable fabric carrying or impregnated with phenolic condensation cementing material such as bakelite varnish. If desired, this sole stiffener member may be previously provided with a frictioned coating 9 of rubber so as to promote its adherence to the rubber sole element 7 when it is vulcanized thereto in the shaping molds. If desired also the edge or attaching portions 8 of this stiffener member may as indicated in Fig. 2 be of relatively less thickness and contain a correspondingly less proportion of such phenolic condensation cementing

and stiffening material so as to facilitate sewing or nailing the heel in place as described in greater detail in my patent above referred to.

- 5 To promote the grip of the shoe sole element on turf or other generally similar ground surface any desired number or arrangement of gripping holes or apertures may be formed therein of the general type 10 sometimes known as golf cups, and it is highly desirable for some purposes to reinforce these gripping apertures by incorporating in the adjacent portions of the shoe sole element reinforcing members or cups 15 comprising one or more layers or thicknesses of canvas or other fabric or fibrous material containing sufficient cured phenolic condensation cementing material so as to make the cup relatively strong and rigid 20 and correspondingly resistant to wear. For this purpose the fabric or other fibrous material may contain thirty to sixty per cent. more or less of such cured phenolic condensation cementing material and about 25 fifty per cent. thereof when incorporated in canvas or generally similar fabric give good results. In this way the edges of these gripping holes or apertures may be maintained without undesirable deformation and the 30 gripping action of the shoe sole element maintained for a correspondingly longer period of service. As indicated in Figs. 1 and 2 these gripping apertures which may be arranged as desired throughout the sole or heel portion or both, may be provided with reinforcing members 4 of general cup form which may comprise several layers 5, 6, of 35 suitable fabric cemented together and stiffened by such phenolic condensation cementing material. For this purpose one or more layers of canvas or heavy knit cotton fabric which is sometimes preferable because of its greater elastic or yielding action may be coated or impregnated with bakelite varnish 40 No. 1, for instance, and then substantially dried and shaped up into the desired form preferably after heating to soften the incorporated cementing material and make the fabric more pliable and yielding. In 45 this way the reinforcing members or cups may be stamped up into the more or less cup-shaped form indicated in Fig. 2, for instance, and cut or trimmed off around the tops, and if desired, the heat of the molds or 50 the preliminary heating of the fabric may act sufficiently to at least partly cure the cementing material, although when a considerable proportion of such cementing material is used it is sufficiently stiff when cold 55 so as to substantially retain the shape given to such an article without any considerable amount of such curing action. If desired, the outer sheet or layer 6 of this fabric may be previously provided with a frictioned 60 coating of rubber 14 in the usual way before 65

the phenolic condensation cementing material is applied to this layer of fabric, or if desired, the inner layer 6 of fabric may be given an unusually heavy coating of such cementing material which during the preliminary heating, molding and shaping of the reinforcing cups or members may be forced sufficiently into the outer layer of fabric to hold the two together until they are molded into and permanently secured to 70 the shoe sole element. This may be effectively done when the shoe sole is molded and vulcanized and as indicated in Fig. 2 the main stiffener member comprising the fabric layers 2, 3, may be simultaneously 75 united to the shoe sole element 7 at this time. By forming this unvulcanized shoe sole element with holes of about the desired shape, the reinforcing cups 4 may be arranged therein and then forced home by 80 suitable mold plugs or elements 12 formed on the upper mold element 10 indicated in a somewhat diagrammatic way as co-operating with the lower mold section 11 in Fig. 2. These molds are of course heated in any 85 suitable way to the desired vulcanizing temperature of 250° to 300° F. more or less and by a vulcanizing and curing treatment of half an hour or an hour or so at such temperatures the vulcanized rubber is thoroughly 90 vulcanized and simultaneously united to the frictional rubber coatings 14, 9 on the stiffening and reinforcing members and the incorporated phenolic condensation cementing material in these members is simultaneously 95 cured so that the entire shoe sole element is strongly cemented together so as to form practically an integral piece. As shown in Fig. 2, a relatively thin cushioning layer of rubber 26 may be arranged between the bottom 25 of some or all of the reinforcing cups and the main stiffening member of the sole so as to somewhat cushion any impact or strong local pressure on the reinforcing cups which is advantageous 100 for some kinds of service. The walls of the reinforcing cups may be given a somewhat flaring or conical shape as indicated and it is usually desirable to have the mold plug 105 12 fitting therein smoothly polished so as to give a smooth inner surface to the reinforcing cups and prevent dirt or other substances from sticking therein so as to promote the self-clearing action of these cups 110 which makes more effective the gripping action on the ground.

The inclination of the walls of these reinforcing cups may of course be varied to suit different conditions and Fig. 3 shows an arrangement in which the cup walls are considerably straighter and in which the bottom 115 15 of the reinforcing cup is shown in substantial contact with the main stiffener member of the rubber shoe sole element 7. When both these reinforcing and stiffening ele- 120 130

ments are forced adjacent to one another and brought into substantial contact in this way in the vulcanizing and curing mold, the phenolic condensation cementing material 5 which they contain may be united by the molding pressure and heat so as to strongly cement these two parts together and rigidly secure the reinforcing cup to the sole stiffening member. This gives an especially strong 10 grip to the shoe sole element particularly when as much as 50 or 60 per cent. of such phenolic condensation cementing material by weight is present in the canvas or other cotton fabric used for the stiffening and reinforcing members. Fig. 4 shows another 15 form of reinforcing cup 13 which has a substantially hemispherical shape. The two layers 5, 6 of impregnated or coated cloth or other fabric may be similarly provided 20 with a frictioned or other rubber coating 14 on the outside to facilitate union with the rubber composition sole element 7 in which the reinforcing cups are embedded and if desired the rounded bottom 16 of this cup 25 may be forced adjacent to or into substantial engagement with the main sole stiffener member 2, 3, so as to be firmly cemented thereto, if desired.

Fig. 5 shows another arrangement in 30 which the reinforcing cup 20 is formed of one or two layers of cloth or other fabric or fibrous material 5, 6, carrying or impregnated with such phenolic condensation cementing material and in this case the reinforcing cup does not have any bottom, but the conical sides may as indicated be directly cemented or secured to the main sole stiffening member so that they may be cemented to the upper layer 3 thereof by the 35 action of such phenolic condensation cementing material in the curing and vulcanizing mold, if desired. In this case the upper layer 3 of the main stiffening member forms the bottom 18 of this reinforced gripping 40 aperture, the whole interior of which may be given a smooth surface and rounded contour at the junction of these two elements by correspondingly shaping and surfacing the molding plug forced into the same during 45 the heat curing treatment. Fig. 6 indicates another arrangement in which the reinforcing member 21 has substantially cylindrical walls and is directly cemented to the main sole stiffening member. Such a reinforcing 50 member, may, if desired, be formed of braided tubular fabric, such as braided cotton hose fabric, for instance, which may advantageously be of rough, irregular contour in some cases. This reinforcing member 55 may be conveniently provided with a frictioned or other rubber coating 14 on its outside and then suitably coated and preferably thoroughly impregnated with such phenolic condensation cementing material and 60 cut into lengths substantially equal to the

thickness of the rubber sole composition into which it is forced during the molding and curing of the sole so that its lower edge may thus be cemented to the sole stiffening member and smooth walls and bottom 19 provided for this gripping aperture while the exposed edge 22 of the reinforcing member may be substantially flush with the wearing surface of the sole element.

Fig. 7 shows another arrangement in 75 which a rubber or other composition sole 17 may be provided with a reinforcing cup 23 formed of one or more layers of fabric 5, 6 carrying or impregnated with such cured phenolic condensation cementing material 80 and vulcanized or secured to the sole composition when the latter is vulcanized preferably in connection with a frictioned or other rubber coating 14 which may, if desired, be previously applied to the reinforcing cup. 85 Such a rubber coating is not, however, necessary in all cases, since when the molding and heat curing is effected under heavy pressure the heat seems to first soften and melt the phenolic condensation cementing material 90 sufficiently so that the rubber in contact therewith forces its way sufficiently into the fibers and interstices of the fabric so as to strongly adhere thereto and give a sufficiently reliable union of the parts especially 95 if the reinforcing cup has the rather rough or irregular outer surface which can be easily provided by the use of a proper grade of fabric.

Fig. 8 shows a somewhat similar arrangement in which a substantially hemispherical type of reinforcing member 24 is directly secured or vulcanized into the rubber composition sole element 17 which may in this instance also have no other stiffening or reinforcing member secured thereto. This reinforcing cup is of generally similar form and construction to the one illustrated in Fig. 4 and described in connection therewith.

This invention has been described in connection with a number of illustrative embodiments, forms, proportions, elements, parts, shapes, materials, compositions, and methods of preparation, production and use, to the details of which disclosure the invention is not of course to be limited, since what is claimed as new and what is desired to be secured by Letters Patent is set forth in the appended claims:

1. The vulcanized shoe sole element comprising a heel portion and provided with a stiffener member of fibrous material carrying cured phenolic condensation cementing and stiffening material secured adjacent one surface of the shoe sole element, said element being formed with a series of ground gripping apertures and reinforcing cups secured in said sole element and forming the walls of said apertures and each comprising a plurality of layers of knit fabric carrying 120

- 30 to 60 per cent. of cured phenolic condensation cementing and stiffening material, said reinforcing cups having substantially smooth inner surfaces and flaring walls to promote their self-clearing action, the bottoms of said cups being secured adjacent to said stiffener member and separated therefrom by a cushioning rubber layer.
2. The vulcanized rubber shoe sole element 10 comprising a heel portion and provided with a stiffener member of fibrous material carrying cured phenolic condensation cementing and stiffening material secured adjacent one surface of the shoe sole element, said element being formed with a series of ground gripping apertures and reinforcing cups secured in said sole element and forming the walls of said apertures and each comprising fabric carrying cured phenolic condensation cementing and stiffening material, said reinforcing cups having substantially smooth inner surfaces and flaring walls to promote their self-clearing action, the bottom of said cups being secured adjacent to said stiffener member and separated therefrom by a cushioning rubber layer.
3. The vulcanized rubber shoe sole element comprising a heel portion and provided with a stiffener member of fibrous material carrying cured phenolic condensation cementing and stiffening material secured adjacent one surface of the shoe sole element, said element being formed with a series of ground gripping apertures and reinforcing cups secured in said sole element and forming the walls of said apertures and each comprising fabric carrying cured phenolic condensation cementing and stiffening material, said reinforcing cups having substantially smooth inner surfaces to promote their self-clearing action, the bottoms of said cups being secured adjacent to said stiffener member.
4. The rubber shoe sole element comprising a heel portion and provided with a stiffener member secured adjacent one surface of the shoe sole element, said element being formed with a series of ground gripping apertures and reinforcing cups secured in said sole element and forming the walls of said apertures and each comprising a plurality of layers of fabric carrying cured phenolic condensation cementing and stiffening material, said reinforcing cups having flaring walls to promote their self-clearing action, the bottoms of said cups being secured adjacent to said stiffener member.
5. The rubber shoe sole element provided with a stiffener member secured adjacent one surface of the shoe sole element, said element being formed with a series of ground gripping apertures and reinforcing cups secured in said sole element and forming the walls of said apertures and each comprising a plurality of layers of fabric carrying cured phenolic condensation cementing and stiffening material, said reinforcing cups having substantially smooth inner surfaces and flaring walls to promote their self-clearing action.
6. The rubber shoe sole element provided with a stiffener member secured adjacent one surface of the shoe sole element, said element being formed with a series of ground gripping apertures and open ended reinforcing members secured in said sole element and forming the walls of said apertures and each comprising a plurality of layers of fabric carrying cured phenolic condensation cementing and stiffening material, said reinforcing members having flaring walls to promote their self-clearing action.
7. The rubber shoe sole element provided with a stiffener member and formed with a series of ground gripping apertures and apertured reinforcing members secured in said sole element and forming the walls of said apertures and each comprising fibrous material carrying cured phenolic condensation cementing and stiffening material, said reinforcing members having flaring substantially conical walls to promote their self-clearing action, the bottoms of said members being secured adjacent to said stiffener member.
8. The rubber shoe sole element provided with a stiffener member and formed with a series of ground gripping apertures and apertured reinforcing members secured in said sole element and forming the walls of said apertures and each comprising fibrous material carrying cured phenolic condensation cementing and stiffening material, the bottoms of said members being secured adjacent to said stiffener member.
9. The rubber shoe sole element formed with a series of ground gripping apertures and apertured reinforcing members secured in said apertures and each comprising fibrous material carrying cured phenolic condensation cementing and stiffening material.
10. The rubber composition shoe sole element formed with a series of ground gripping apertures and reinforcing cups secured in said sole element and forming the walls of said apertures and comprising fabric carrying cured phenolic condensation cementing and stiffening material, said reinforcing cups having substantially smooth inner surfaces and flaring walls to promote their self-clearing action.
11. The rubber composition shoe sole element formed with a series of ground gripping apertures and apertured reinforcing members secured in said sole element and forming the walls of said apertures and comprising cured phenolic condensation cementing and stiffening material, said reinforcing members having flaring walls to promote their self-clearing action.
12. The composition shoe sole element

formed with a series of ground gripping apertures and apertured reinforcing members secured in said apertures and comprising fabric carrying cured phenolic condensation cementing and stiffening material.

13. The rubber shoe sole element provided with a stiffener member carrying cured phenolic condensation cementing and stiffening fibrous material, said element being formed with a series of ground gripping apertures and apertured outwardly flaring reinforcing members secured in said sole element and forming the edges of said apertures at the tread surface of said sole element and each comprising fibrous material

carrying cured phenolic condensation cementing and stiffening material, the bottoms of said members being secured adjacent to said stiffener member.

14. The rubber shoe sole element provided with a stiffener member, said element being formed with a series of ground gripping apertures and apertured reinforcing members secured in said sole element and forming the edges of said apertures at the tread surface of said sole elements and each comprising fibrous material carrying cured phenolic condensation cementing and stiffening material. 20 25

HENRY C. EGERTON.
